UNITED STATES PATENT OFFICE.

ROBERT D. WILLIAMS, OF ALBANY, NEW YORK.

DESIGN FOR A SPOON.

SPECIFICATION forming part of Design No. 20,711, dated May 5, 1891.

Application filed March 21, 1891. Serial No. 385,950. Term of patent 3½ years.

To all whom it may concern:

Be it known that I, ROBERT D. WILLIAMS, a citizen of the United States, residing at the city of Albany, county of Albany, and State 5 of New York, have invented a certain new and ornamental Design for Spoons, of which the following is a description.

The design is illustrated in the accompanying drawing, which shows a spoon having 10 a conventional handle and bowl, both more or less ornamented. At the upper end of the handle and on its broadest part is a pattern of scroll-work with broken and irregular edges, and upon its surface is depicted a representation or view of the completed State 15 Capitol, at Albany, New York, showing the main front and entrance. Below the scroll, some of their tops mingling with its foliated border, is a bunch of the reeds known as "cat-tails," the stems of which, bunched together 20 and slightly waving, form the greater longitudinal portion of the handle. Below the cluster of the tops of the reeds a band crosses the handle diagonally, on which is the word 25 "Albany." A little below this band on the handle, the space between being partly filled by two heads of the said reeds, another band crosses the handle diagonally, on which are the letters and marks "N. Y." The said word 30 "Albany" and letters and marks "N. Y." are inconspicuous, and are not of the essence of the design. Still farther down another band crosses the handle in the same general direction 35 as the other bands, and below this another band, one end of which is forked, partly crosses the handle. The whole effect of these

various bands is that of a ribbon binding the bunch of cat-tails together. The words and letters mentioned are read with the handle of the spoon held vertically. Just below the 40 ends of the said stems and directly above the top of the bowl of the spoon is the top of a beaver's hut. Crouched closely on the ground in front of the hut and busily engaged in gnawing on the branch of a tree is a beaver. 45

Upon a portion of the surface of the bowl of the spoon is a representation of a part of a fish-net, the edge of which runs diagonally from a point at the top of the bowl just under the tip of the beaver's tail to a point 50 about at the middle of the opposite side of the bowl. A fish is shown as caught and held by the meshes of the net.

In the drawing, A represents the bowl of the spoon; B, the fish-net; C, the fish; D, the 55 beaver; E, the tree-branch; F, the top of the beaver's hut; G, the bunch of cat-tails; H, the handle of the spoon; K, the series of bands crossing the handle; L, the word "Albany"; M, the letters and marks "N. Y.;" 60 N, the scroll, and O the Capitol.

Having thus described my invention, what I claim, and desire to secure by Letters Patent, is—

The design for spoons herein described and 65 illustrated.

In witness whereof I have hereunto signed my name this 19th day of March, 1891.

ROBERT D. WILLIAMS.
